Attorney

UNITED STATES PATENT OFFICE.

JOSEPH F. WIREBACK, OF PITTSBURGH, PENNSYLVANIA.

POSITIVE OR MASTER CAST FOR THE REPRODUCTION OF NEGATIVE OR SOCKETED ARTIFICIAL LIMBS.

1,310,937.

Specification of Letters Patent. Patented July 22, 1919.

Application filed January 17, 1918. Serial No. 212,172.

To all whom it may concern:

Be it known that I, JOSEPH F. WIREBACK, a citizen of the United States, residing at Pittsburgh, in the county of Allegheny and State of Pennsylvania, have invented new and useful Improvements in Positive or Master Casts for the Reproduction of Negative or Socketed Artificial Limbs, of which the following is a specification.

10 This invention relates to certain new and useful improvements in a positive or master cast which is used in connection with a lathe for the reproduction of a negative or socketed artificial limb, also the method of 15 forming the positive cast.

The main object of this invention is the production of a cast pattern, which during its formation is properly centered upon a support or shaft by which the pattern can 20 be accurately secured in position in the lathe without further adjustment.

Another object of the present invention, 25 is the production of a cast pattern which not only causes the formation of a socket in exact accordance with the stump, but also guides the cutting tool in hollowing out the lower part of the artificial limb.

Other objects and aims of the invention, 30 more or less broad than those stated together with the advantages inherent, will be in part obvious and in part specifically referred to in the course of the following description, and the scope of the protection contemplated will appear from the claims.

35 In the accompanying drawings, which are to be taken as a part of the specification, and in which I have shown a merely preferred form of the embodiment of the invention, Fig. 1 is a view of a leg stump with 40 the mold of the same applied, Fig. 2 is a view of the mold with the closed end portion removed, Fig. 3 is a sectional view illustrating the manner of assembling the parts and filling to produce the positive pattern, 45 Fig. 4 is a side elevation of the cast after the removal of the mold and Fig. 5 shows a view of the finished cast after the plastic material used in filling the extension 4 has been cut away to the desired shape.

50 Referring more in detail to the drawings, wherein similar letters of reference indicate like parts throughout the several views, 1 indicates the stump of a human limb, upon which, in the present instance, it is desired 55 to fit an artificial limb. About this stump

there is cast a portion 2 preferably formed by first placing a so called stocking over the stump, then wrapping thereabout a plurality of layers of plasterized gauze bandage. This is allowed to remain until set and is 60 then removed from the stump. The closed end 3 of this portion 2 is then removed. So far described only a mold of the actual stump is produced and in order that the final production of the artificial limb may 65 be hollowed out below its socketed portion, in the usual way, to produce a limb of extreme lightness, the following construction is added to the casting 2. An extension 4, which may be made of paper, card board or 70 any suitable material, is fitted about the stump casting adjacent its end 5. This extension is hollow and preferably of a gradual tapering formation from end to end.

The mold with its extension is then centered over a shafting or arbor 6 and temporarily secured in position by being fastened to the block 7 into which one end of the shaft 6 extends. Plastic material 8 of 75 any desirable substance is then poured with- 80 in the mold and extension 4, completely filling the same and centrally embedding the shaft 6. To assist in the positive anchoring of the shaft within the plastic substance, there is provided a plurality of cross 85 pins 9.

After the plastic mass has set, the mold and extension is cut away from the same and the block is slid from the end of the shaft, thereby leaving a positive cast pattern 90 properly centered upon the shaft.

When the pattern is completed it will be noted that there is an offset 10 at the point of junction of the tapering portion 4 and the socket forming portion 2 which being 95 in this positive pattern will result in an enlargement of the hollowed out portion of the resultant limb immediately below the socket. The offset is smoothed down with a rasp just enough to allow ample room at 100 the end of the socket for the reception of the tender portion of the stump and prevent constant jarring incident to walking, from continually pulling the side portions of the stump backward, which will ultimately result in an exposure of the bone. The remainder of the extension is then shaped 105 down to the proper tapered size required.

This pattern, when inserted into a turning lathe such as is commonly known in the 110

art will guide the tracing member, which in turn controls the movement of the cutting tool, and therefore accurately produce the socket for the human stump and then continue to produce the hollowed out portion of the artificial limb below the socket.

It is intended that all matter contained in the above description or shown in the accompanying drawings shall be interpreted as illustrative and not in a limiting sense.

It is also to be understood that the language used in the following claims is intended to cover all the generic and specific formation of the invention herein described and all statements of the scope of the invention, which as a matter of language, might be said to fall therebetween.

I claim:

1. The method of forming a positive turning pattern for the reproduction of a socketed artificial limb which consists in taking a mold of the stump, centering said mold about a shaft, then filling the mold with a plastic substance embedding the shaft therein, then cutting the said mold from about the set plastic substance.

2. The method of forming a positive turning pattern for the reproduction of a socketed artificial limb which consists in taking a mold of the stump then removing the closed end of said mold, securing an extension to the mold then centering said mold and extension about a shaft, filling said mold and extension with a plastic substance embed-

ding the shaft therein, then cutting said mold and extension from about the set plastic substance.

3. In a positive limb pattern for the production of a socketed artificial limb comprising an integrally cast socket forming portion and a lower limb boring portion.

4. In a positive limb pattern for the production of a socketed artificial limb comprising an integrally cast socket forming portion and a lower limb boring portion, and a supporting shaft centrally embedded therein.

5. In a positive limb pattern for the production of a socketed artificial limb comprising an integrally cast socket forming portion and a lower limb boring portion and a supporting shaft embedded therein through the longitudinal centers of said portions.

6. In a positive limb pattern for the production of a socketed artificial limb comprising an integrally cast socket forming portion and a lower limb boring portion, an offset adjacent the junction of the socket and limb boring portions to provide an enlargement at a corresponding place in the negative form.

In testimony whereof I affix my signature in the presence of two witnesses.

JOSEPH F. WIREBACK.
